UNITED STATES PATENT OFFICE.

MORGAN J. HAMMERS, OF DETROIT, MICHIGAN.

DESIGN FOR A MOTOR-VEHICLE BODY.

49,609.

Specification for Design.

Patented Sept. 5, 1916.

Application filed April 15, 1916. Serial No. 91,491. Term of patent 7 years.

To all whom it may concern:

Be it known that I, MORGAN J. HAMMERS, a citizen of the United States of America, residing in the city of Detroit, Wayne county, Michigan, have invented a new, original, and ornamental Design for Motor-Vehicle Bodies, of which the following is a specification, reference being had to the accompanying drawing, forming part thereof.

The figure is a side elevation of a motor vehicle body, showing my new design.

I claim:

The ornamental design for a motor vehicle body, as shown.

MORGAN J. HAMMERS.

Witnesses:

THERESA LIEBERMAN,
JEFFERSON G. THURBER.
